(57) **CLAIM**

I claim the ornamental design for a scooter, as shown and described.

DESCRIPTION

FIG. 1 is a perspective view of my new design taken from the upper rear right side thereof;

FIG. 2 is a perspective view of my design taken from the upper front right side thereof;

FIG. 3 is a right side elevation of my new design;

FIG. 4 is a front elevation view showing my new design;

FIG. 5 is a rear elevation view showing my new design;

FIG. 6 is a top plan view of my new design; and,

FIG. 7 is a bottom plan view of my new design.

The left side elevation view is identical to the right side elevation.
